UNITED STATES PATENT OFFICE.

ISAAC FREED, OF HARRISBURG, PENNSYLVANIA.

SAFE FOR PASSENGER-CARS.

SPECIFICATION forming part of Letters Patent No. 606,336, dated June 28, 1898.

Application filed March 30, 1897. Serial No. 629,974. (No model.)

To all whom it may concern:

Be it known that I, ISAAC FREED, a citizen of the United States, residing at Harrisburg, in the county of Dauphin and State of Pennsylvania, have invented certain new and useful Improvements in Safes for Passenger-Cars; and I do declare the following to be a full, clear, and exact description of the invention, such as will enable others skilled in the art to which it appertains to make and use the same.

My invention relates to improvements in safes, and more particularly to that class of safes intended for the temporary safe deposit of the valuables usually carried by a traveler; and the object is to provide such a receptacle as will fulfil the wants of the public in this respect.

To this end the novelty consists in the construction, combination, adaptation, and arrangement of the parts of the safe, as will be hereinafter more fully described, and particularly pointed out in the claim.

In the accompanying drawings the same reference characters indicate the same parts of the invention.

Figure 1 is a perspective view of one form of my safe as applied to a sleeping-car. Fig. 2 is a vertical section of the safe as fitted in a permanent structure. Fig. 3 is a transverse section of the safe. Fig. 4 is a plan view of one of the electric connections. Fig. 5 is a cross-section on the dotted line $\alpha\alpha$ of Fig. 4. Fig. 6 is a horizontal section of the door connections; and Fig. 7 is a diagrammatic plan of the alarm-circuit, showing the door connection and the cut-out switch.

1 represents the safe proper, and while in the present instance it is shown rectangular in form it may be of any approved shape to conform to the space to which it is to be permanently fitted.

The top 2 and bottom 3 are each provided with longitudinal retaining-recesses 4, which receive the inner ends of the stay-braces 5, the outer ends of which are turned at an angle to the body of the brace to form an arm 6, and by means of which the said braces may be fixed to any adjacent solid portion of the structure in such a manner as to prevent their displacement without destroying the contiguous parts to which they are attached. In prac-

tice I prefer to secure the inner ends of these stay-braces from the inside of the safe, and for this purpose I have shown set-screws 7, 55 bearing against the braces and projecting into the safe from the top 2 and bottom 3, although any other suitable means may be employed to secure the ends of said braces from within the safe.

8 represents the hinged door, and it is provided with a suitable lock and key, in addition to which I provide a rotary switch 9', operated by a removable key 9, the switch forming part of the alarm-circuit, the wires 10 10 65 of which are concealed in the structure to prevent the possibility of their being tampered with, and a signal is placed in the conductor's or porter's station, and in addition to this an indicator, which is connected to the common 70 circuit and indicates the attempt to tamper with a particular safe in the car.

The interior of the safe is fitted up into suitable apartments for the reception of such articles of jewelry and other valuables usually carried by a traveler, and as the safe itself, being made of steel, is non-combustible, as well as burglar-proof, nothing short of absolute destruction of the safe itself will harm the contents.

14 represents an automatic switch forming part of the alarm-circuit in connection with the conductor-wires 10 10. This switch 14 is located within the safe, and it comprises the spring-actuated rod 16, the projecting end 15 85 of which extends into the path of the door 8. The opposite end of this rod 16 terminates in a contact-finger 17, which normally rests between the two contact-points 18 and 19, and therefore the slightest movement of the door 90 outward or inward will cause the finger 17 to close the alarm-circuit through one or the other of said contact-points and sound the alarm. Consequently an attempt to force the door inward will be frustrated, as well as an 95 attempt to open it.

Of course it will be understood that the rightful owner of the key 9 may cut out the switch so controlled, and thereby open the ordinary lock to have access to the safe at all 100 times without sounding the alarm.

Of course it will be understood that the bifurcated contact-point 18 19 forms one terminal of the alarm-circuit and the spring con-

tact-finger 17, which normally rests between but without touching either, forms the other terminal, so that if the door be forced inward the finger 17 will close the alarm-circuit 5 through the point 18, while if the attempt be made to force the door outward the same alarm-circuit will be closed by said finger 17 coming in contact with the point 19, and as the key 9 simply opens or closes the conductors 10 10, forming a part of the alarm-circuit above mentioned, it follows that when said circuit is closed by said key 9 the safe is protected, and of course when the circuit is broken or interrupted by the same means the door 15 may be opened without the points 17 and 19 operating to sound the alarm.

Although I have specifically described the construction and relative arrangement of the several elements of my invention, I do not de-

sire to be confined to the same, as such changes 20 or modifications may be made as clearly fall within the scope of my invention without departing from the spirit thereof.

Having thus fully described my invention, what I claim as new and useful, and desire to 25 secure by Letters Patent, is—

A safe of the class described, provided with retaining-recesses, in combination with a series of stay-braces and means, substantially as described, for securing the ends of said 30 braces within said safe, as and for the purpose set forth.

In testimony whereof I hereunto affix my signature in presence of two witnesses.

ISAAC FREED.
